UNITED STATES PATENT OFFICE

2,582,654

WINDOW BEAD AND FASTENER THEREFOR

John S. Saban, Detroit, Mich.

Application March 15, 1951, Serial No. 215,756

3 Claims. (Cl. 16—220)

1

The present invention relates to certain new and useful improvements which, broadly speaking, have to do with sliding sash windows of the double-hung type but has reference, more particularly, to insertable and removable stop-beads and specially constructed fasteners therefor.

As implied in the preceding general statement of the invention, insertable and removable stop-beads are notoriously old. Where sliding sashes are embodied in the window frame construction the parting strip or bead is fixed and interposed between the upper and lower sashes and the inwardly disposed stop-bead is attachable and detachable in whole or in part. By removing a pair of removable stop-beads it is impossible for a housewife to lift the lower sash out, wash the window pane interiorly and exteriorly and then replace both the sash and the stop-beads. It is also a matter of common knowledge that many and varied styles and forms of stop-bead fasteners have been offered for manufacture and use.

One improvement herein under advisement has to do with a stop-bead of the insertable and removable type which is provided with dowel pins which are adapted to be removably fitted into sockets provided therefor in the window casing, said bead having a compressible packing strip or element which is interposed between the bead and window casing and which, when tightly compressed, provides a satisfactory weather-seal between the stop-bead and casing.

Primarily, the invention has to do with the improved stop-bead fastener. This is characterized by a unique bracket which is adapted to be fastened in a window casing, the same having a sheath-like receiver carrying selectively usable bolt-accommodating ears. A bolt is removably mounted in one of the ears and held in place by a thumb-nut and the opposite end of the bolt has a keeper hook which is selectively engageable with keeper holes in the shank portion of an adjustable clamping and retaining hook. The shank is slideable in the sheath and the bill portion of the hook is clamped and held against the stop-bead for purposes of holding the latter in place.

Other objects and advantages will become more readily apparent from the following description and the accompanying sheet of illustrative drawings.

In the accompanying sheet of drawings, wherein like numerals are employed to designate like parts throughout the views:

Figure 1 is a fragmentary elevational view 55

2

showing a double-hung window construction with the lower sash bodily removable, with the stop-bead of said sash and with the manually regulable fasteners for said stop-bead;

Figure 2 is an enlarged fragmentary horizontal section on the line 2—2 of Figure 1, looking in the direction of the arrows and with parts in both section and elevation;

Figure 3 is a vertical section at right angles to Figure 2, said section being on the vertical line 3—3 of Figure 1, looking in the direction of the arrows;

Figure 4 is a perspective view, of an exploded type, with the components systematically bracketed together; and

Figure 5 is a reduced fragmentary perspective view of the insertable and removable stop-bead.

Reference may be had first to Figure 1 wherein essential portions of a double-hung sash window construction are shown. Here, one of the members of the window casing is denoted at 6 with the stool denoted at 8 and the apron at 10. The upper sash, of a sliding type, is denoted at 12 and the lower sash at 14. In Figure 2 the fixed parting strip or bead is denoted at 16. Here is also shown the casing member 18 and window frame part 20. In practice, only the lower half-portions of the stop-beads are insertable and removable. For simplification, only one such bead will be hereinafter referred to. To this end, the stop-bead, which is of any appropriate material, generally wood, is of elongated rectangular form and denoted by the numeral 22. It has a beveled upper end 24 which fits in place with a corresponding bevel on the fixed stop-bead 26. Said stop-bead 22 is provided with positioning and retaining dowel pins or studs 28—28 and these fit into sockets provided therefor in the casing member 18 as best shown in Figure 2. The packing strip 30 is denoted by the numeral 30 and is interposed between the bead and casing member. This packing strip may be of compressible cork, rubber or the like. When it is under compression it serves to provide an effective weather-seal between the bead 22 and the casing member 18 as is obvious.

The stop-bead fasteners are employed in suitable numbers and perhaps two on each vertical side of the sash 14. It is necessary to describe but a single fastener and the description proceeds accordingly. The attaching bracket or fixture is denoted by the numeral 32 and this is of sheet metal or equivalent sheet material. It is in the form of a pre-cut and suitably stamped plate which is bent intermediate its ends to provide an open-ended channel which constitutes a sheath

34, the side walls of the sheath having outstanding attaching flanges 36 and 38. These are apertured to accommodate wood screws or the like 40 as shown in Figure 2. The sheath is provided at its outer end with upper and lower apertured ears 42 and 44 which are selectively used, depending on whether the bracket is at the right or left of the window construction and which serves to accommodate the readily applicable and removable shackling bolt 46. The threaded end 48 of the bolt is passed through the selected ear in the manner shown to accommodate the thumb nut 50. The opposite end of the bolt is provided with a lateral keeper hook 52. The flanges 36 and 38 have curved terminals or end portions 54—54 which fit against and conform to the coacting surface of the window casing member 6 as shown in the drawings. The stop-bead engaging, retaining and slack take-up hook is denoted by the numeral 56. The hook proper is denoted at 58 and reaches into the pocket of the window construction and engages and holds the stop-bead in place in the manner shown best in Figure 2. The shank 60 is telescopically and removably fitted for sliding adjustment in the sheath 34. Said shank is also provided with keeper holes to accommodate the keeper hook and these holes are denoted at 62. What with the fastener set up and adjusted as shown in Figure 2, it is obvious that the keeper hook 52 is engaged in a selected one of the keeper holes 62. The hook 58 is engaged with the stop-bead and the nut is tightened on the bolt for purposes of rendering the fastener effective and holding the stop-bead securely in place in the position shown.

With a fastener of this construction it is possible for the housewife to insert and remove stop-beads by unhooking same in an obvious manner. Then the lower sash may be taken out, washed and turned and again fastened in place. The upper sash may be pulled down for washing and this may be accomplished without removing same from the window frame.

Novelty is predicated on the dowel pin-equipped stop-bead 22 and the fastener therefor shown and herein specifically described.

It is thought that persons skilled in the art to which the invention relates will be able to obtain a clear understanding of the invention after considering the description in connection with the drawings. Therefore, a more lengthy description is regarded as unnecessary.

Minor changes in the shape, size, materials and arrangement of parts may be resorted to in actual

practice without departing from the spirit and scope of the invention, as claimed.

Having described the invention, what is claimed as new is:

- 5 1. A stop-bead fastener of the class described comprising a hook including a bill portion and a shank portion, said shank portion having selectively usable keeper holes, an attaching bracket, means slidably mounting said shank on said bracket, a bolt detachably and adjustably mounted on said bracket and having a hook at one end, said hook constituting a keeper and being selectively engageable with the keeper holes in said shank.
- 10 15 2. A stop-bead fastener of the class described comprising a bracket having an open-ended sheath, a hook having a shank slidably in said sheath, said shank being provided with selectively usable keeper holes, and a bolt mounted on said bracket, said bolt having a nut on one end and a lateral keeper hook on the opposite end, said keeper hook being selectively engageable with the stated keeper holes.
- 20 25 3. A stop-bead fastener of the class described comprising a bracket, said bracket embodying a sheath having attaching flanges, said sheath being provided at one end with outstanding selectively usable bolt attaching ears, a bolt having a screw-threaded end portion passing through one of said ears and provided with a nut engaging the said one ear, said bolt being provided at its opposite end with a lateral keeper hook, and a bead engaging hook having a shank slidably in said sheath, said shank being provided with selectively usable keeper holes and said keeper hook being adjustably connectible with said keeper holes.

JOHN S. SABAN.
